UNITED STATES PATENT OFFICE.

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE.

PLUNGER MECHANISM FOR BLINDSTITCH SEWING MACHINES.

Application filed April 26, 1927. Serial No. 186,672.

This invention relates to new and useful improvements in plunger operating mechanisms for blind stitch sewing machines generally, although the invention is particularly 5 adapted for use in connection with a blind stitch sewing machine for felling coat linings, as is shown and described in my co-pending application Serial No. 186,674, filed on the 26th day of April, 1927.

10 In felling operations generally, it is desirable to provide a blind stitch sewing machine in which the needle will enter and emerge from the upper face of the base layer during alternate needle reciprocations and 15 for this purpose a lower plunger is provided for projecting a node of said base layer into needle penetrating position immediately prior to alternate needle penetrating strokes.

One of the principal objects of my invention is to provide a plunger mechanism for 20 the purpose set forth in which differential reciprocatory strokes will be imparted to the plunger whereby on one stroke of the plunger the base layer will not be engaged 25 by said plunger and on the next stroke of the plunger the base layer will be elevated so as to form a node therein for the entrance by the needle.

Another object of the invention is to provide 30 a plunger mechanism which includes a rock shaft, a rotary driving shaft, and toggle connections between said shafts whereby differential reciprocatory strokes will be imparted to the plunger.

35 Another object of the invention is to provide a plunger operating mechanism which is extremely simple in construction and which is positive in its action.

With these and other objects in view 40 which will more fully appear, the nature of the invention will be more clearly understood by following the description, the appended claims, and the several views illustrated in the accompanying drawings.

45 In the accompanying drawings which illustrate one form of my invention:

Figure 1 is a rear elevation of a blind stitch sewing machine equipped with a plunger mechanism embodying my invention,

50 Figure 2 is a bottom plan view, parts thereof being shown in section to better disclose the plunger mechanism,

Figure 3 is a sectional view taken at right 55 angles to Figure 2,

Figure 4 is an elevation showing the toggle driving connections for the plunger, the parts in full lines showing their positions when the plunger is at the upper end of its short stroke, and the dotted lines showing 60 the positions of the parts when the plunger is at the lower end of its short stroke.

Figure 5 is a similar view showing in full lines the positions of the parts when the plunger is at the upper end of its long 65 stroke, and showing in dotted lines the positions of the parts when the plunger is at the lower end of its long stroke, and

Figure 6 is a series of diagrammatic illustrations showing the relation between the 70 plunger and the base layer during a complete cycle of operations.

Like reference numerals designate corresponding parts throughout the several figures of the drawings.

Referring to the accompanying drawings, I have illustrated a blind stitch sewing machine of the well known Lewis type and this machine is illustrated in my co-pending application Serial No. 186,674, filed on the 26th 80 day of April, 1927.

This machine includes a base 5, a work supporting arm 6, a standard 7, an overhanging arm 8, and a stitching head 9 supported by the overhanging arm directly 85 above the outer end of the work arm 6. The needle mechanism is not shown in these drawings as it forms no part of the present invention, but for the purpose of reference, the needle mechanism associated 90 with this particular machine is shown and described in my co-pending application Serial No. 180,527, filed on the 2nd day of April, 1927.

Fixed to the bottom portion of the stitching head 9 is a presser foot 10 and cooperating with this presser foot to feed the material through the machine is a work presenting mechanism which I have illustrated 95 as a whole by the reference numeral 11. 100 This work presenting mechanism includes an intermittent feeding mechanism of the 4-motion type and these four motions are transmitted to the feed dog through the medium of the rock shafts 12 and 13 which 105 are journaled in the work arm 6, the rock shafts being oscillated by pitmen 14 and 15 respectively which are driven from the main rotary shaft 16 which is journaled in the upper end of the standard 7 and within the 110

overhanging arm 8. This work presenting mechanism 11 includes a plunger 17 which is slidably mounted in the outer end of the work arm 6 for vertical reciprocations. The 5 plunger 17 is reciprocated vertically from a rock shaft 18 journaled in the work arm 6 through the medium of a connection which I have indicated as a whole by the reference numeral 19 and which is shown and described in Patent 1,588,133 issued to me on 10 June 8, 1926.

As previously stated, means are provided for imparting differential reciprocatory strokes to this plunger, or in other words, 15 means are provided for imparting short and long reciprocatory strokes to the plunger. For this purpose, I have provided the toggle operating mechanism shown in detail in Figures 4 and 5. Fixed to the rotary 20 driving shaft 16 directly above the standard 7 is an eccentric 20 and a gear pinion 21, the latter driving a "1 to 2" gear 22 which is located within the standard 7 and journaled on a stub shaft 23 fixed to said 25 standard. Fixed to the outer face of the driven gear 22 is an eccentric pin 24 and journaled on this pin is a guide 25 in which is slidably mounted a lever 26 having its upper end formed with a sleeve 27 which 30 surrounds the eccentric 20. Secured to the plunger rock shaft 18 is a rock arm 28, at the outer end of which is pivotally connected, as at 29, the lower end of a substantially vertically disposed link 30. The upper 35 end of the link 30 is pivotally connected, as at 31, to the outer end of an arm 32 which is pivoted, as at 33, to the base 5 at a point above the plunger rock shaft 18. A link 34 has its upper end pivotally connected, as at 40 35, with the lower end of the lever 26 and the lower end of the link 34 is pivotally connected, as at 36, with the pivoted arm 32. It will, therefore, be seen that the lever 26 and the link 34 cooperate to form a toggle 45 connection between the rotary driving shaft 16 and the plunger rock shaft 18. It will also be noted that the lever 26 is slidably supported for endwise movement upon a shiftable fulcrum, the fulcrum partaking of 50 a circular path of travel due to the rotation of the gear 32.

When the parts are in the positions shown in full lines in Figure 4, the plunger 17 is located at the upper end of its short stroke and directly below the fabric F, as indicated at A in Figure 6. In this position the high point of the eccentric 20 is directly above the shaft 16. The shaft 16 rotates in the direction indicated by the arrow, and 55 inasmuch as the gear connection is a "1 to 2" coupling, it follows that when the high point of the eccentric 20 is moved 180°, the eccentric pin 24 of the gear 22 will be moved downwardly and towards the left for a distance of 90°. As the eccentric 20 is thus

moved for 180°, the lever 26 slides in the guide 25 and consequently the position of the lever 26 is shown in dotted lines in Figure 4. In this position of the parts, the pivot 35 has been lowered and also been 70 moved towards the left. This results in the plunger rock shaft 18 being oscillated to move the plunger 17 downwardly to the lower end of its short stroke as indicated at B in Figure 6. The eccentric 20 is then turned for 180° and simultaneously the gear 22 is rotated so as to move the eccentric pin 24 upwardly towards the left for a distance of 90°, or to the full line position shown in 75 Figure 5. As a result, the pivot 35 of the toggle connection is at its highest extreme position towards the left, and consequently the pivoted arm 32 is oscillated for a greater distance with the result that the plunger rock shaft 18 will be given a correspondingly increased amount of oscillation, and the plunger 17 will be moved to the upper end of its long stroke for forming a node f in the base layer, as shown at C in Figure 6. The eccentric 20 is then rotated for 180° and simultaneously the eccentric pin 24 is moved 80 upwardly and towards the right for 90°, as shown by dotted lines in Figure 5, thus resulting in oscillating the rock shaft 18 so as to move the plunger 17 downwardly 85 to the lower end of its long stroke as shown at D in Figure 6. This completes the cycle 90 of operation. When the plunger 17 is at the upper end of its long stroke, the pivot 35 is in the horizontal plane indicated by 95 the line x in Figure 5, and when the plunger is at the upper end of its short stroke, the pivot 35 is in the horizontal plane indicated by the line y in Figure 4. Thus the distance 100 between the horizontal lines x and y indicate the difference in vertical movements of the link 34 when the plunger 17 is at the upper 105 end of its short and long strokes.

It is of course to be understood that the details of structure and arrangements of 110 parts may be variously changed and modified without departing from the spirit and scope of my invention.

I claim:

1. A plunger mechanism for blind stitch 115 sewing machines comprising in combination, a vertically reciprocatory plunger, means for imparting differential reciprocatory strokes to said plunger including a rock shaft operatively connected to the plunger, 120 a rotary driving shaft, and connections between said shafts including a toggle.

2. A plunger mechanism for blind stitch 125 sewing machines comprising in combination, a vertically reciprocatory plunger, means for imparting differential reciprocatory strokes to said plunger including a rock shaft operatively connected to the plunger, 130 a rotary driving shaft, and connections between said shafts including a toggle com-

- prising a lengthwise movable lever having a shiftable fulcrum, a link connecting the lever and rock shaft, and means for shifting the fulcrum of the lever.
5. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a gear driven by said rotary shaft, a guide for slidably engaging the lever eccentrically journaled on said gear, a rock arm on said rock shaft, and a link connecting said lever and said rock arm.
10. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, and connections between said shafts including a toggle comprising a lengthwise movable lever having a fulcrum movable about a circular path, a link connecting the lever and rock shaft, and means for moving said fulcrum in its circular path.
15. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
20. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
25. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
30. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
35. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
40. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a shiftable fulcrum for the lever having sliding connection therewith, a rock arm on said rock shaft, a link connecting said lever and rock arm, and means for continuously shifting said fulcrum.
45. sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a gear driven by said rotary shaft, a guide for slidably engaging the lever eccentrically journaled on said gear, a rock arm on said rock shaft, and a link connecting said lever and said rock arm.
50. 7. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, and connections between said shafts including a toggle comprising a lengthwise movable lever having a fulcrum movable about a circular path, a link connecting the lever and rock shaft, and means for rotating the fulcrum about its circular path once during every two revolutions of the rotary shaft.
55. 8. A plunger mechanism for blind stitch sewing machines comprising in combination, a vertically reciprocatory plunger, means for imparting differential reciprocatory strokes to said plunger including a rock shaft operatively connected to the plunger, a rotary driving shaft, an eccentric fixed to said driving shaft, a lever journaled on said eccentric, a gear pinion fixed to the rotary shaft, a 1-to-2 gear driven by said pinion, a guide for slidably engaging the lever eccentrically journaled on said gear, and a connection between the lever and the rock shaft for oscillating the latter.
60. In testimony whereof I hereunto affix my signature.
65. 70. 75. 80. 85. CHARLES W. MUELLER.
